UNITED STATES PATENT OFFICE.

JOHN GAMBLE, OF PHILADELPHIA, PENNSYLVANIA.

BASE-BALL MITT.

No. 836,378.

Specification of Letters Patent.

Patented Nov. 20, 1906.

Application filed April 12, 1906. Serial No. 311,313.

To all whom it may concern:

Be it known that I, JOHN GAMBLE, a citizen of the United States, residing at Philadelphia, Pennsylvania, have invented certain new and useful Improvements in Base-Ball Mitts, of which the following is a specification.

My invention relates to improvements in base-ball mitts or gloves; and the object of the invention is to provide a glove which will have a firm outer edge without its being too rigid and the pocket of which will be of a soft and yielding nature, allowing the ball to sink deeply and the force or impact of the ball be taken up by the walls of the outer rim or edge.

With these and other objects in view the invention includes the novel features of construction hereinafter described, and particularly pointed out in the claim.

The invention is illustrated in the accompanying drawings, in which—

Figure 1 is a plan view, partly broken away, and Fig. 2 is a transverse sectional view on line $\alpha\alpha$ of Fig. 1.

The glove shown in the drawings is of the well-known type in which a palm portion and a back portion are separably connected together, so as to permit of the insertion and removal of the complete pad. Heretofore these pads have been generally made of a plurality of layers of felt with a portion cut out or removed from the center to form a recess or pocket. With a glove or body in this form of pad there is considerable softness or puffiness on the outer edges adjacent to the pocket, which is very objectionable

and is only overcome by constant use—in other words, until the glove becomes thoroughly broken in. In order to obviate these objections, I form the pad in the manner shown in the accompanying drawings, in which I have shown at 3 a pad, of felt, composed of one or more layers of uniform thickness throughout and shaped to have the exterior edge conform to the shape of the glove. Upon the palm side of the glove and extending around in proximity to the said outer edge for a suitable distance toward the center is located a filling 4, of loose wool or cotton, which is covered and held in place by a covering 5, of canvas, muslin, or the like. I prefer to continue this covering around and inward on the back side of the pad, the edges being stitched together through the substance of the pad.

Having thus described my invention, what I claim is—

A pad for base-ball mitts, comprising a body composed of felt, a ring of loose padding material upon one face of the body portion and a cover for confining said loose material in place embracing said loose material and the edge of the body portion, the sides of said cover being stitched together through said body portion on the inner edge of the ring, substantially as described.

In testimony whereof I affix my signature in presence of two witnesses.

JOHN GAMBLE.
